ADVERTISING DOOR PULL

Ernest R. Erickson, Des Moines, Iowa, assignor to
 C. E. Erickson Company, Incorporated, Des
 Moines, Iowa, a corporation of Iowa

Application February 20, 1939, Serial No. 257,323

10 Claims. (Cl. 40—125)

An object of my present invention is to provide an advertising door pull of simple and inexpensive construction particularly adapted for mounting on a door or the like, and the parts thereof being so constructed and arranged that one advertising plate with its advertising material thereon may be used regardless of whether the handle of the structure is to be used on a right or left hand door.

More particularly, it is the object of my invention to provide an advertising door pull comprising a handle plate and an advertising plate which are telescopically associated with each other so that either end of the advertising plate can be associated with the handle member to adapt the device for either right or left hand mounting depending on the door to which it is to be applied.

A further object is to provide an extension plate for the free end of the advertising plate to span the width of a door within given limits so as to give a symmetrical and finished appearance to the advertising door pull regardless of the fact that doors vary in width and that the door pull will in actual practice be applied to different widths of doors.

Still a further and more specific object is to provide an advertising door pull which can be readily formed of sheet metal and in which one advertising plate can be used regardless of whether the handle is to be applied on the right hand side or the left hand side of a door, the handle for this purpose being mounted on a T-shaped handle plate which is symmetrical about its horizontal axis and the leg of which telescopically coacts with the advertising plate in such manner that either end of the plate can be telescopically associated therewith.

The foregoing objects as well as other and further objects of the invention will be apparent from the following description, accompanying drawing and appended claims. An embodiment of the invention is illustrated in the accompanying drawing in which the views thereof are as follows:

Figure 1 is a front elevation of a left hand door with my advertising door pull applied thereto.

Figure 2 is a front elevation of a somewhat wider right hand door with my door pull mounted thereon.

Figure 3 is an enlarged sectional view on the line 3—3 of Figure 1.

Figure 4 is an exploded perspective view of my advertising door pull; and

Figure 5 is an enlarged sectional view on the line 5—5 of Figure 1.

On the accompanying drawing I have used the reference character H to indicate generally a handle member, A an advertising plate, and E an extension plate. The handle member H consists of a handle plate having a leg 10 and arms 12 and 13. A handle 14 is connected with the plate 12 as by nuts 15 mounted on reduced threaded extensions of the rodlike handle 14 (see Figure 3).

The handle plate 10—12—13 may be formed of sheet metal or the like, preferably with a bevelled flange therearound and including particularly a pair of bevelled flanges 16 on the upper and lower sides of the leg 10. The arms 12 and 13 are provided with openings 17 to receive mounting elements such as screws 18 while the leg 10 is provided with an opening 19.

The advertising plate A consists of an elongated sheet of metal having bevelled flanges 20 terminating in hooked flanges 21. The flanges 20 and 21 coact with the flanges 16 for telescopic association of the plate A relative to the handle member H. Openings 22 and 23 are provided in the plate A adjacent the ends thereof for selective registry with the opening 19 depending upon which end of the plate A is telescopically associated with the leg 10. A fastening element such as a bolt 24 (see Figure 3) is located in the registered openings 19 and 22, or 19 and 23 as the case may be, to secure the members H and A together as a unit.

The extension plate E has a pair of bevelled side flanges 25 and a bevelled end flange 26. Adjacent the flange 26 an opening 27 is provided. The extension plate E is adapted to assume either a non-extended position as shown in Figure 1 and by solid lines in Figure 3, or an extended position as shown in Figure 2 and by dotted lines in Figure 3. When in the non-extended position the opening 27 registers with the opening 23 (or with the opening 22, as the case may be) to receive a mounting screw 28. When in the extended position the openings just mentioned do not register and the opening 27 is thereupon adapted to receive a mounting screw 29 (see Figures 2 and 3).

From the foregoing description taken in connection with the accompanying drawing it will be obvious that either end of the advertising plate A may be telescopically associated with the leg 10 of the handle member H depending on whether the handle is to be mounted left or right hand. The arms 12 and 13 of the member H and the handle rod 14 are symmetrical about the horizontal axis of the leg 10 so that a similar and balanced appearance of the handle with respect to the advertising plate is secured regardless of

which way the door pull is to be mounted. This is obvious from a comparison of Figures 1 and 2 with each other.

Providing the openings 22 and 23 in each end of the advertising plate permits use of the fastening bolt 24 to connect the handle H and the plate A together as a unit regardless of whether the handle is to be mounted left or right hand. The extension plate E may then be used in non-extended position for a narrow door as shown by solid lines in Figure 3 in such manner that its end flange 26 gives a finished appearance to the free end (or end opposite the handle H) of the plate A. When the door is wider as in Figure 2, the extension plate E may be extended to make the entire device conform in a more balanced manner to the size of the door and a screw 29 instead of a screw 28 can be used to mount the free end of the device on the door. Due to the telescopic connection between the parts A and E the part E can be extended to any desired position to accommodate different doors within the limits of the length of the member E.

Having described one specific embodiment of my advertising door pull together with the adjustment, installation and operation thereof, I desire it to be understood that the form selected is for the purpose of facilitating the disclosure of the invention rather than to limit the form or details which the invention may assume. It is to be further understood that various modifications, adaptations and alterations may be applied to the specific form disclosed to meet the requirements of commercial practice without in any manner departing from the spirit and scope of the present invention as defined by the appended claims.

I claim as my invention and desire to secure by Letters Patent of the United States:

40 1. In a door pull, a handle plate adapted to be attached to the surface of a door adjacent one side thereof, an advertising plate telescopically connected with and extending laterally from said handle plate at a point substantially midway between the upper and lower ends thereof, said advertising plate being adapted for either end thereof to connect with and be supported by said handle plate and an extension plate for telescopic connection with the other end of said advertising plate.

45 2. In an advertising door pull, a handle plate for attachment to a door adjacent one side thereof, an advertising plate connected with said handle plate and extending substantially horizontally therefrom, said advertising plate being adapted for either end thereof to connect with said handle plate means to effect such connection whereby said handle plate and said advertising plate constitute a unit, one end of said advertising plate being supported by said handle plate, and means for supporting the other end of said advertising plate.

50 3. In an advertising door pull, a handle member comprising a T-shaped handle plate having openings for mounting elements and a handle on the arms of said handle plate and substantially aligned with said arms, an advertising plate telescopically co-acting with the leg of said T-shaped handle plate, an opening in said leg, an opening in each end of said advertising plate to selectively register with the opening of said leg depending upon which end of the advertising plate is associated with said leg, a fastening element through said registered openings and an extension element telescopically associated

with the free end of said advertising plate, said extension element having an opening to receive a mounting element.

4. In an advertising door plate, a handle member comprising a T-shaped handle plate, a handle on the arms thereof and substantially aligned with said arms, an advertising plate having either end arranged and adapted to telescopically coact with the leg of said T-shaped handle plate, a fastening element through said advertising plate and said leg to retain said advertising plate and handle plate assembled as a unit and an extension element telescopically associated with the free end of said advertising plate.

5 10 15 5. In a door pull, a handle member comprising a vertically elongated handle plate, a handle thereon, an advertising plate coacting with said handle plate, and supported thereby, perforations in said handle plate, openings in each end of said advertising plate to selectively register with the perforations in said handle plate depending upon which end of the advertising plate is associated with said handle plate, and a fastening element through said registered openings.

20 25 30 35 6. In an ornamental door bar, a handle member comprising a vertically elongated T-shaped handle plate, a handle thereon, an advertising plate having either end thereof telescopically coactable with the leg of said T-shaped handle plate, and means for securing the end of the advertising plate associated with said leg to the leg whereby the advertising plate and handle plate form a unitary door bar, with said advertising plate supported at one end by said handle plate, an extension element telescopically associated with the free end of said advertising plate for supporting that end of said advertising plate, said extension element having an opening to receive a mounting element.

40 45 50 55 7. In an advertising door plate, a handle member comprising a T-shaped handle plate, a handle thereon, the leg of said handle plate being provided with bevelled flanges along its side edges, an advertising plate having bevelled flanges along its side edges terminating in hooked flanges to telescopically receive said leg of said T-shaped handle plate, an opening in the leg of said handle plate, openings in the ends of said advertising plate to selectively register with the opening of said leg and an extension plate having bevelled flanges received in the bevelled and hooked flanges of said advertising plate whereby said extension plate is telescopically associated with the advertising plate and supported thereby, said extension plate having an opening adjacent one end thereof and a bevelled flange along said end.

60 65 70 8. In an advertising handle pull, a vertically elongated handle plate member including a handle and a horizontal leg, said leg being provided with flanges along its side edges, an advertising plate having flanges along its side edges terminating in hooked flanges to telescopically receive said leg and be supported thereby at one end and an extension plate having flanges received in the flanges and hooked flanges of said advertising plate whereby said extension plate is telescopically associated with the advertising plate for supporting said plate at its other end.

75 9. In a door bar, a handle plate, a horizontal leg portion thereon provided with bevelled flanges along its side edges, and an advertising plate having bevelled flanges along its side edges terminating in hooked flanges to telescopically

receive said leg of said handle plate and be supported thereby, an opening in said leg, openings in the ends of said advertising plate to selectively register with the opening of said leg and fastening means through the registered openings.

10. In a door pull, a handle plate adapted to be attached to the surface of a door adjacent one

side thereof, an advertising plate connected with, supported by and extending laterally from said handle plate at a point substantially midway between the upper and lower ends thereof, said advertising plate being adapted for either end thereof to connect with and be supported by said handle plate. 5

ERNEST R. ERICKSON.
